(57) CLAIM

We claim the ornamental design for a rear view mirror frame, as shown and described.

DESCRIPTION

FIG. 1 is a side view illustrating a rear view mirror frame. FIG. 2 is an enlarged front perspective view illustrating the design shown in FIG. 1.

FIG. 3 is an enlarged front view illustrating the design shown in FIG. 1.

FIG. 4 is an enlarged top view illustrating the design shown in FIG. 1.

FIG. 5 is an enlarged rear view illustrating the design shown in FIG. 1.

FIG. 6 is an enlarged view illustrating the side of the design shown in FIG. 1; and,

FIG. 7 is an enlarged view illustrating an opposite side of the design shown in FIG. 1.

The broken line showing of the environment is for illustrative purposes only and forms no part of the claimed design. The broken lines which define the boundaries of the claimed design form no part thereof.

No ornamental features are illustrated on the surface shown in FIG. 5 because this surface is not visible during normal operation of the rear view mirror frame (e.g., this surface is typically covered by a mirror). Therefore, this surface forms no part of the claimed design.
